DESIGN FOR A PORTABLE BATTERY LIGHT FOR REFRIGERATOR CABINETS OR THE LIKE

Walter B. Schulte, Madison, Wis., assignor to
C. F. Burgess Laboratories, Inc., Chicago, Ill.,
a corporation of Delaware

Application June 1, 1936, Serial No. 62,920

Term of patent 14 years

To all whom it may concern:

Be it known that I, Walter B. Schulte, a citizen of the United States, residing at Madison, in the county of Dane and State of Wisconsin, have invented a new, original, and ornamental Design for a Portable Battery Light for Refrigerator Cabinets or the like, of which the following is a specification, reference being had to the accompanying drawing, forming part thereof.

Fig. 1 is a perspective view, Fig. 2 is a side elevation, and Fig. 3 is a rear elevation, of a portable battery light for refrigerator cabinets or the like, showing my new design.

I claim:

The ornamental design for a portable battery light for refrigerator cabinets or the like, as shown.

WALTER B. SCHULTE.
